MERCHANTISE DISPLAY RACK OR SIMILAR ARTICLE

William A. Miles, Dallas, Tex.

Application May 26, 1950, Serial No. 10,198

Term of patent 7 years

(Cl. D80—9)

To all whom it may concern:

Be it known that I, William A. Miles, a citizen of the United States, residing at Dallas, in the county of Dallas and State of Texas, have invented a new, original, and ornamental Design for Merchandise Display Rack or Similar Article as shown, of which the following is a specification, reference being had to the accompanying drawing, forming part thereof.

The dotted showing is for illustrative purposes only.

I claim:

The ornamental design for a merchandise display rack or similar article, substantially as shown and described.

WILLIAM A. MILES.
